BEVERAGE BOTTLE

Ferdinand S. Barbiers, Lancaster, Ohio, assignor to Clicquot Club Company, Millis, Mass.

Application May 21, 1956, Serial No. 41,556

Term of patent 14 years

(Cl. D58—8)

Figure 1 is a front elevational view of a beverage bottle, showing my new design; and Figure 2 is a horizontal cross-sectional view thereof, taken on the line 2—2 of Figure 1.

The rear and side views of the bottle not shown are the same, except for the plain label space, as the front view shown.

I claim:

The ornamental design for a beverage bottle, as shown and described.
